UNITED STATES PATENT OFFICE.

JOSEPH E. BOND, OF MAYWOOD, ILLINOIS.

BRICKMAKING-MACHINE.

No. 874,482.

Specification of Letters Patent.

Patented Dec. 24, 1907.

Application filed July 27, 1906, Serial No. 328,123. Renewed May 16, 1907. Serial No. 373,975.

To all whom it may concern:

Be it known that I, JOSEPH E. BOND, of Maywood, in the county of Cook and State of Illinois, have invented a certain new, useful, and Improved Brick-Making Machine, of which the following is a full, clear, and exact description, such as will enable others skilled in the art to which it appertains to make and use the same.

10 My invention relates to the art of manufacturing fire bricks and has special reference to improvements in machines for molding fire bricks. Heretofore it has been considered impractical to mold fire bricks by machinery. When attempts have been made to do so it has been found that the machine molded bricks could not withstand the intense heat of furnaces. Consequently it has been a custom with all fire brick manufacturers, to use the hand process in making all high grade standard bricks, and articles of special shape. The hand process consists in taking a lump of clay of the proper consistency in the hand, and after making a ball or 20 "wauk" of it, throwing it into the mold with sufficient force to cause the ball to fill out the mold and to firmly unite with the clay that has already been thrown therein. The mold is then struck off and slicked, and 25 the wet or green brick is then turned out upon the pallet to dry, before being fired. This process involves heavy work and it requires a high degree of skill to properly throw the clay when molding the more intricate shapes.

30 The object of my invention is to provide a mechanical substitute for the present manual process of manufacturing fire bricks.

The special object of my invention is to 40 provide a machine for forming and throwing balls or "wauks" of clay into molds with the same or greater force than is now expended in the hand process.

45 With these objects in view, my invention consists in a machine whereby successive quantities of clay of equal size and density may be forcibly and automatically discharged by fluid pressure into the molds with uniform force.

50 More specifically my invention consists in a machine of the class mentioned, comprising a clay reservoir, a passageway or barrel communicating with said reservoir, means for feeding clay through said reservoir and into said barrel, a reciprocating plunger having a duct or ducts and located in said barrel,

means for reciprocating said plunger and means for automatically connecting the duct or ducts in said plunger with a source of fluid under pressure, at a certain point in 60 the descent of the plunger to forcibly expel the clay from the barrel and into a mold.

My invention further consists in a machine of the class mentioned, having means for automatically controlling the plunger to prevent its operation except when the clay is in condition to quickly fill the barrel when opened to the reservoir.

My invention further consists in a movable table or conveyer, whereby molds of large 70 dimensions may be shifted in the process of filling, to properly receive the clay; and which may be utilized for quickly and easily conveying successive molds, to and from the clay throwing machine.

75 My invention consists further in certain novel constructions, combinations and arrangements of parts, all as hereinafter fully described and particularly pointed out in the claims.

80 My invention will be more readily understood by reference to the accompanying drawings, which form a part of this specification and in which;

Figure I is a vertical section of a brick 85 molding machine embodying my invention.

Fig. II is an enlarged horizontal section taken on the line II—II of Fig. I, Fig. III is an enlarged section taken on the irregular line 90 III—III of Fig. I, Fig. IV is a sectional view of the main valve, on an enlarged scale, parts being broken away to better illustrate the device. Fig. V is a horizontal section taken on the line V—V of Fig. IV. Fig. VI is a vertical section taken on line VI—VI of Fig. 95

V. Fig. VII is a plan view of the mold conveying mechanism. Fig. VIII is a sectional view taken on line VIII—VIII of Fig. VII.

Fig. IX is a similar view taken on line 100 IX—IX of Fig. VII. Fig. X is a vertical sectional view similar to Fig. I, illustrating a modification thereof in which the plunger is actuated by a crank and connecting rod, and in which, mechanism is shown for automatically controlling the machine in order that the

105 clay may be discharged therefrom, only at such times as it is of the proper density. Figs. XI & XII are detail plan views of two forms of perforated plates carried by the lower end of the plunger.

110 Referring to the drawings, 1, indicates a pug-mill of the usual type, or of any pre-

ferred form, comprising a hopper, a shaft, 2, a pulley, 2', and blades, 3, carried by the shaft. The pug-mill communicates with the receiving chamber, 4, hereinafter termed the 5 reservoir, and the shaft, 2, is extended into said reservoir, and in this case is shown as provided with a rotary screw, 5, by which the material is fed through the reservoir. The pug-mill and reservoir are supported in any 10 suitable manner; as for example by beams, 6, shown in Figs. II & III. I do not wish to limit myself to the screw feeding device, 5, as a steam actuated piston or other means might be employed for the same purpose.

15 The discharge end of the reservoir, 4, is reduced in diameter and communicates with a transverse passageway or clay barrel, 7, open at its lower end. The preferred sectional form of the said passage is rectangular and 20 elongated, as indicated in Fig. II. Fitted air-tightly but slidably within the passageway, 7, is a plunger, 10, shown at the lower end of its stroke in Fig. I. This plunger is 25 secured to a crosshead, 11, mounted between guides, 12, (Fig. III) which are supported by a hollow casting, 13, forming a housing for the crosshead and having an opening, 14, in its top through which passes the drive-rod, 15. This rod may be recipro- 30 cated by any preferred mechanism or motive power. As shown in Fig. I it is constituted by or is connected to a piston rod, 16, of a steam engine, 17, having a valve chest, 18, valve rod, 19, rock arm 20, and other parts 35 necessary to reciprocate the rod, 15. A belt driven mechanism for operating the rod, 16, is illustrated in Fig. X and will be hereinafter described.

When the plunger, 10, is at its uppermost 40 position its lower end will register with the point, 21, thus permitting a portion of the plunger space, or clay barrel, to be filled with clay by the action of the feeding device. In descending, the plunger, 10, forces this clay into the lower part, 8, of the barrel.

The plunger is formed with an interior opening or duct, 22, passing vertically there- 50 through and also through the lower portion, 11', of the crosshead, 11. Said opening or duct may be divided into two or more divisions by partitions, 23, as shown in Fig. III; but such partitions are not an essential feature of the plunger construction.

It will be observed that the lower end of 55 the plunger is partially closed by a metal plate, 54, secured thereto, and that the plate is provided with a plurality of orifices, 55. Two preferable arrangements of these orifices are shown in Figs. XI & XII. The majority 60 are located at or adjacent to the ends of the plate, 54, and one or more are arranged along the central or neutral axis of the plate, and spaced farther apart than those adjacent the ends. This arrangement, I have ascertained 65 by experiment, is desirable for preventing

partial expulsion of a slug or "wauk" of clay: owing to the fact that, where an open plunger is used, the tendency is for the central portion of the slug to be blown out while the remainder is retarded by friction with the 70 walls of the barrel. By the arrangement of fluid-pressure orifices shown, it is obvious that the fluid pressure upon different parts of the slug will be proportioned to the frictional resistance opposing the movement of the different portions of the slug; in other words, the pressure will be greater upon the ends than upon the middle of the slug. This exertion of greater pressure upon the ends of the 75 slug than upon the center thereof has the tendency to form the slug into one mass or ball, and in this way more closely approximates hand work. The orifices are preferably made bell-mouthed or flaring toward the lower face of the plate, as shown; the inclined surfaces thus presented to the slug of clay offer greater resistance to the material so that the material will not penetrate entirely through the orifices when the plunger 80 is forced down.

The admission of the fluid under pressure to the upper end of the duct, 22, may be controlled by valve mechanism of any suitable construction. A preferred form of valve mechanism for this purpose is shown in Fig. I 95 and in detail in Figs. III, IV & V. 24 indicates a slide valve mounted within a valve chamber, 25, upon a seat, 11', formed by the bottom of the crosshead, 11. It is provided with upward projections, 24', engaged by 100 collars, 26, on the stem, 27, of a double piston, 28, fitted within the cylindrical ends of the valve chamber, 25. The fluid under pressure is admitted into said valve chamber through a hose or other suitable connection, 105 30, a flexible connection being employed owing to the fact that the valve chest, 25, reciprocates with the crosshead, 11. The valve, 24, is provided with a port, 31, which registers intermittently with the fluid passage, 22, of 110 the plunger. When said valve is at one end of its stroke it assumes the position shown in Fig. I. When the valve is at the opposite end of its stroke the port, 31, registers with the duct, 22, and the fluid under pressure 115 passes from the valve chamber into the hollow plunger, 10, to eject the "wauk" from the passageway, 7. However this action is but momentary as the valve is immediately reversed, thereby cutting off the fluid from the plunger. The valve may be actuated by a purely mechanical device, or by a partly mechanical and partly fluid-operated device. The latter construction is preferred by me 120 for the reason that it permits of a quicker 125 movement of the valve, thus effecting a saving of the steam or compressed air used for expelling the slugs of clay into the molds. The piston ends, 28, above referred to, are employed in order to utilize fluid pressure for 130

actuating the valve, 24. As most clearly shown in Fig. V, the ends of the valve chamber, 25, are respectively connected by ports, 32, to a primary valve chamber, 33, in which 5 is mounted a small slide valve, 34, having a rod, 35, which extends through a gland or stuffing box. The rod, 35 is adjustably secured to a slide, 36, which is supported by brackets, 37 & 38, the latter having an integral portion, 38', by which it is secured to one 10 end of the valve chamber, 25.

The primary valve, 34, is shown in its normal position in Fig. V. Fluid enters the valve chamber, 33, through an inlet opening 15 (not shown) and passes through one of the ports, 32, into the right hand end of valve chamber, 25; thereby holding the piston, 28, and the main valve, 24, in a normal position. Between the ports, 32 and valve, 34, is an 20 exhaust port, 40, which communicates with the atmosphere. If the valve stem, 35, be moved to the right it will uncover the left hand inlet port, 32, admitting the fluid into the left hand end valve chamber, 25, and the 25 piston, 28, and valve, 24, will thereby be moved to the right, causing the port, 31, to register as aforesaid, and the other inlet port, 32, will be connected, through valve, 34, to the exhaust port, 40. The reverse movement 30 of valve rod, 35, restores valve, 34, and piston, 28, and valve, 24, to normal positions by similar action at the opposite end of the valve chamber, 25.

The valve stem slide, 36, is reciprocated 35 preferably by means of mechanism shown in Figs. IV, V, & VI. The said slide, 36, carries a lateral stud, 41, which projects through a slot in a depending, swinging arm, 42, pivoted on a pin, 43, held by a standard, 44, 40 which is shown as integral with bracket, 38. Arm, 42, carries at one side thereof a roller 45, which projects into a cam groove, 46, formed in an upright plate, 48, supported by a bracket, 13', which is secured to the housing, 45 13. The central portion of said cam groove is curved or offset as indicated at 47, to permit lateral movement of the roller, 45, as the arm, 42, descends; said arm being carried down by the downward movement of the 50 crosshead, 11, and connected parts. As the roller, 45, reaches a certain point in its downward movement it is moved laterally into the offset portion of the groove, 46, by the action of a cam, 49, having an inclined face, 49', and 55 pivotally mounted upon a pin, 50. The downward movement of this cam is limited by a stop shoulder, 51, but the cam is free to be moved upwardly to the position indicated in dotted lines; further upward movement 60 being prevented by an upper stop shoulder, 52. As soon as the roller, 45, has passed the pivotal cam, 49, it engages the portion, 47, of the cam groove, which returns it and the connected parts to normal position. The lower 65 straight portion of the groove prevents fur-

ther lateral movement thereof. When the crosshead, 11, and connected parts ascend, the roller, 45, lifts the cam, 49, out of its path and is thereby permitted to complete its upward stroke in a straight line; consequently 70 the primary valve, 34, is not actuated during the up stroke of the parts named. The devices which actuate the primary valve, 34, are so adjusted that they do not act until the plunger, 10, has descended almost to its lowermost position, as it is not necessary to admit the steam or air into the plunger previous 75 to this time.

I wish it understood that I do not limit my invention to the forms of valves nor the particular construction herein shown, as it is obvious that the desired results may be effected by the use of any suitable valve mechanism whereby fluid pressure may be exerted upon the slug at the proper time to discharge the 85 same from the spout.

At certain times, it may occur that the clay reservoir, 4, will be only partially filled with clay, in which case, the transverse passage or plunger space above the spout, 8, 90 might not be completely filled with clay of proper density after every up-stroke of the plunger, 10. Therefore it is desirable to provide means by which the action of the plunger will be suspended until a sufficient quantity of clay shall have accumulated to properly fill the plunger space or barrel. A suitable means for this purpose would consist in a device controlled by the pressure of clay within the reservoir and mechanically or 100 otherwise connected to the plunger-actuating mechanism in such a manner as to suspend the operation of said mechanism when the above-described condition occurs. Thus, a regulating device controlled as stated may 105 be connected to the throttle-valve of the steam engine cylinder, where the plunger is so driven. In the drawings, I have illustrated a device for the above named purpose, in connection with a modified form of 110 plunger-driving mechanism.

I have already stated that the plunger, 10, may be actuated by a belt-driven mechanism, and in Fig. X have illustrated such a device. A shaft, 84, carried by journal brackets, 85, is provided with a crank, 86, connected by a rod, 87, to the upper end of the crosshead, 11. A belt-driven pulley, 88, may be keyed upon the shaft, 84, but when my automatic regulating device is employed said pulley will be loosely mounted thereon. To that end I connect the pulley, 88, by a suitable friction clutch to a notched disk, 89, keyed to the shaft, 84, and normally free to rotate; and provide suitable means operable 120 by the pressure of clay in the reservoir, for preventing the rotation of the disk and consequent reciprocation of the plunger when the pressure in said reservoir falls below normal. With this in view, I provide the reser- 130

voir with a cylindrical recess, constituting a piston chamber, and preferably locate it above, or at one side of, the feed screw, 5. Mounted in this chamber or cylinder is a piston or valve, 92, which may be either weighted down or pressed upon by a spring, 93, as shown. A rod, 94, connected to this piston or valve, passes out through a central opening in a head, 95, of the chamber, and is directly or indirectly connected to a bell crank lever, 90. Normally the piston or valve, 92, in the chamber, 91, is held up or outwardly against the pressure of spring, 93, by the normal pressure of the clay in the reservoir, 4. This normal clay pressure by acting through rod, 94, and lever, 90, maintains the clutch, 89, in operative position, so that the plunger, 10, is normally in action. Whenever the clay pressure or density within the reservoir, 4, is materially decreased (which may at times occur owing to the condition of the material) the opposed pressure of the spring, 93, will force the piston or valve, 92, inwardly, and this movement, acting through the rod, 94, will throw the free arm of the bell crank lever inwardly into the path of a notch, 89', on the disk. This will arrest the disk, 89, against rotation, the friction connection between the disk and the pulley permitting the latter to continue to rotate. The lever, 90, and notch, 89', are so located that when the machine is stopped the plunger will be in its uppermost position. In this way the clay is permitted to accumulate within the reservoir, 4, until its pressure becomes again sufficient to throw out the valve or piston, 92, which will then permit the plunger, 10, to resume its operation. In this connection, it may be stated that a positive clutch may be substituted for the friction device described if considered preferable thereto, and I do not wish to limit myself to any particular type of clutch for the purpose named.

In Fig. I, 53 indicates a mold for a brick, tile or any similar article, arranged in position to receive material from the spout, 8. The molds to be used with this machine may be placed upon the floor, or upon elevated supports, either movable or immovable, of any preferred kind. For obvious reasons it is desirable to employ horizontally movable supports, so that each mold may be shifted with respect to the spout, 8, while being filled. The mold-supporting and conveying device illustrated in Figs. I, VII, VIII & IX is well adapted to meet the requirements of this machine. As shown, the carriage, comprising longitudinal bars, 56, rigidly connected by cross-bars, 56', provided with supporting rollers, 57, is mounted for transverse movement upon trackways, 58. At the ends of the carriage are two broad faced pulleys, 59, having end shafts, 60, suitably journaled on the members, 56, and carrying an endless belt, 62. Upon the upper run of this

belt the molds are supported. Between the pulleys, 59, the upper run of the belt may be supported in any suitable manner, preferably by transverse rollers, 63, which may be spaced as close together as thought desirable. For actuating the belt when so desired, I provide one of the shafts, 60, with a sprocket-wheel, 64, and drive the same by a chain, 65, connecting sprocket, 64, to a drive-sprocket, 66, fixed on a transverse shaft, 67, held by bearings, 68, and provided with a crank or hand wheel, 69. For transverse movement of the carriage, the carriage may be pushed or pulled along the trackways, 58, by the operator, or the same result may be effected by operation of a hand wheel through intermediate mechanism. As shown, a second transverse shaft, 70, with bearings, 71, is provided at one end with a hand wheel, 72, and at the other end with a bevel gear wheel, 73, meshing with a bevel gear wheel, 74, fixed upon a shaft, 75, disposed parallel to the carriage, 56. Adjacent to its bearings, 76, shaft, 75, is provided with sprocket-wheels, 77, at a suitable distance from the shaft 75, is a parallel shaft, 78, carrying drive-sprockets, 79, which are connected to sprockets, 77, by chains, 80. One or both of the carriage bars, 56, are connected to the sprocket chains, 80; whereby movements of the chains, 80, will be communicated to the carriage. The shaft bearings, 76, are shown as supported by transverse bars, 81, which are mounted on longitudinal sills or bars, 82.

It will be noticed that the hand wheels, 69 & 72, are arranged close together so that they may be easily operated simultaneously by one person. In this way the mold resting on the belt, 62, may be moved in any direction at the will of the operator. A series of molds may be placed upon the belt, 62, in rows and be brought successively under the spout, 8, by manipulation of the hand wheels, the filled molds being removed from the belt in any preferred manner.

The operation of the machine as shown in Fig. I is substantially as follows: The mold to be filled is placed upon the belt, 62, below the spout, 8, and the plunger, 10, is put into action by admitting steam to the cylinder, 17. Power is applied to shaft, 2, by a belt (not shown) on the pulley, 2', and the clay or other material is tempered in the pug-mill, 3, or fed into the pug-mill in its tempered state as may be desired, in the usual manner, and is fed through the reservoir, 4, by the action of the screw, 5, and pressed against the inner face of the plunger, 10. When the plunger ascends the plunger space is filled with clay. The plunger descends, thereby detaching a slug of the clay from the mass, and the steam or compressed air is quickly admitted into the interior of the plunger and as quickly shut off. The steam or air pressure is suffi-

100

105

110

115

120

125

130

cient to forcibly discharge the slug of clay through the spout, 8, into the mold. This operation is repeated until the mold is filled; the mold being shifted if necessary by the operator while being filled. Or the plunger may be stopped in its highest position, until sufficient clay has accumulated in the spout to fill the mold at one discharge, if the mold be small enough. After being removed from 10 the conveying belt, the mold is treated in the manner usual in the hand process.

The operation of one form of automatic clay pressure regulator has been fully described above.

15 My reason for preferring steam to compressed air as the medium for causing the discharge of clay into the molds is that steam condensing upon the clay moistens the edges of the "wauk" and causes successive wauks 20 or quantities to more perfectly unite in the mold.

In the claims, by the word "clay" I wish to be understood as meaning material of any kind which is capable of being worked like 25 clay.

As various modifications of my invention will suggest themselves to one skilled in the art I do not limit myself to the specific construction and arrangement of parts given 30^{es} herein.

Having thus described my invention, I claim as new and desire to secure by Letters Patent:

1. In a brick molding machine, a clay reservoir provided with a discharge spout or barrel; means for detaching a slug of clay from the mass within the reservoir, and means for discharging the slug from the spout by fluid pressure in said spout, substantially as described.

2. In a brick molding machine, a clay reservoir provided with a discharge spout, means for pressing the mass of clay within the reservoir toward said spout, means for 45 detaching a slug of clay from the mass, and means for discharging the slug from the spout by fluid pressure in the said spout, substantially as described.

3. In a brick molding machine, a clay reservoir having a discharge spout; a plunger for detaching a slug of clay from the mass, and means for discharging a slug from the spout by fluid pressure in the said spout, substantially as described.

55 4. In a brick molding machine, a clay reservoir having a discharge spout; means for pressing the mass of clay toward said spout, a plunger for detaching a slug of clay from the mass, and means for discharging the slug from the spout by fluid pressure in the said spout, substantially as described.

5. In a brick molding machine, a clay reservoir provided with a plunger space and a discharge spout, a hollow plunger working in 60 said spout, means for momentarily admitting

a fluid under pressure into the spout at each stroke of said plunger, whereby a slug of clay will be suddenly and forcibly discharged through said spout, and means for feeding the clay into the plunger space, substantially 70 as described.

6. In a brick molding machine, a clay reservoir provided with a plunger space and a discharge spout; a hollow plunger working in alinement with said spout, means for momentarily admitting a fluid under pressure into the plunger at each stroke thereof, whereby a slug of clay will be suddenly and forcibly discharged through said spout, means for reciprocating said plunger, and 75 means for feeding the clay into the plunger space, substantially as described.

7. In a brick molding machine, a clay reservoir provided with a plunger space and a discharge spout; a hollow plunger working in alinement with said spout, means for momentarily admitting a fluid under pressure into the plunger at each stroke thereof, whereby a slug of clay will be suddenly and forcibly discharged through said spout, 80 means for reciprocating said plunger, and means for feeding the clay into the plunger space, substantially as described.

8. In a brick molding machine, a clay reservoir provided with a plunger space and a discharge spout; a pug-mill feeding into said reservoir, means for pressing the clay into the plunger space, a hollow plunger working in alinement with said spout, and means for momentarily admitting a fluid under pressure 95 into the plunger at each stroke thereof, whereby a slug of clay will be suddenly and forcibly discharged through the spout, substantially as described.

9. In a brick molding machine, a clay reservoir having a plunger space and a discharge spout; a hollow plunger working in said plunger space, a valve for momentarily admitting a fluid under pressure into the plunger, means for actuating the valve at 100 each reciprocation of the plunger, and means for pressing the clay in the reservoir into said plunger space, substantially as described.

10. In a brick molding machine, a clay reservoir having a plunger space and a discharge 115 spout; a hollow plunger working in the plunger space, a valve for admitting a fluid under pressure into the plunger, means for momentarily opening the valve at each reciprocation of the plunger, and means for pressing the 120 clay into said plunger space, substantially as described.

11. In a brick molding machine, a clay reservoir having a plunger space and a discharge spout; a hollow plunger working in alinement 125 with said spout, a fluid-pressure-operated valve for momentarily admitting a fluid under pressure into the plunger, a primary valve controlling the movements of the first named valve, means to actuate the primary 130

valve at each reciprocation of the plunger, and means to force clay into said plunger space, substantially as described.

12. In a brick molding machine, a clay reservoir provided with a plunger space and a discharge spout; a hollow plunger reciprocating through the plunger space, means for momentarily admitting a fluid under pressure into the plunger at the end of the operative 10 stroke of the plunger, and means for pressing clay into the plunger space when the plunger ascends, substantially as described.

13. In a brick molding machine, a clay reservoir provided with a plunger space and a 15 discharge spout; a hollow plunger having a perforated or partially open lower end working in said plunger space, means for momentarily admitting a fluid under pressure into the plunger at each reciprocation thereof, 20 and means for pressing clay into the plunger space, substantially as described.

14. In a brick molding machine, a clay reservoir provided with a plunger space and a discharge spout; a hollow plunger having a 25 perforated or partially open lower end working in said plunger space, a valve for momentarily admitting a fluid under pressure into the plunger at each reciprocation thereof, and means for pressing clay into the plunger 30 space, substantially as described.

15. In a brick molding machine, a clay reservoir provided with a plunger space and a discharge spout; a hollow plunger having a 35 perforated or partially open lower end working in said plunger space, a fluid-pressure-operated valve for momentarily admitting a fluid under pressure into the plunger at each reciprocation thereof, and means for pressing clay into the plunger space, substantially as 40 described.

16. In a brick molding machine, a clay reservoir having a plunger space and a discharge spout; a hollow plunger having a perforated lower end working in said plunger space, a 45 valve for admitting a fluid under pressure into the plunger, a primary valve controlling the operation of the aforesaid valve, means for momentarily opening the primary valve at each reciprocation of the plunger, and 50 means to press clay into the plunger space, substantially as described.

17. In a brick molding machine, a clay reservoir means for feeding clay by pressure into said reservoir; a plunger adapted to detach a 55 slug of clay from the mass within the reservoir, means to reciprocate the plunger, and automatic means for suspending the operation of the plunger when the quantity of clay within the reservoir becomes insufficient, 60 substantially as described.

18. In a brick molding machine, a clay reservoir having a plunger space and a discharge spout, a plunger adapted to detach a slug of clay from the mass within the reservoir, 65 means to actuate the plunger, and means to

suspend the operation of said actuating means when the quantity of clay within the reservoir becomes insufficient, substantially as described.

19. In a brick molding machine, a clay reservoir having an extension adapted to receive a portion of clay from the reservoir, a movable spring-pressed member within said extension, said member being movable by variation of density of the clay, a plunger 70 adapted to detach a slug of clay from the mass, plunger-actuating mechanism, and means actuated by connections with said movable member for suspending the action of the plunger when the density of the clay 75 within the reservoir becomes insufficient, 80 substantially as described.

20. In a brick molding machine, a clay reservoir an extension chamber opening thereinto, a movable spring-pressed member with- 85 in said chamber, said member being movable by the variation of the density of the clay, a plunger adapted to separate a slug of clay 90 from the mass, plunger-actuating mechanism, and means operated by connections with said movable member for suspending the action of the plunger when the density or quantity of the clay within the reservoir becomes insufficient, substantially as described.

21. In a brick molding machine, a clay 95 reservoir provided with a plunger space and a discharge spout; a hollow plunger working in alinement with said spout, means for momentarily admitting a fluid under pressure into the plunger at each stroke thereof, 100 whereby a slug of clay will be suddenly and forcibly discharged through said spout, and a rotating worm for feeding the clay into the plunger-space, substantially as described.

22. In a brick molding machine, a clay 105 reservoir provided with a plunger space and a discharge spout; a hollow plunger working in alinement with said spout, means for momentarily admitting a fluid under pressure into the plunger at each stroke thereof, 110 whereby a slug of clay will be suddenly and forcibly discharged through said spout, means for reciprocating the plunger, and a rotating worm for feeding the clay into the plunger space, substantially as described. 115

23. In a brick molding machine, a clay reservoir having a plunger space and a discharge spout; a pug-mill feeding into said reservoir, a rotating worm for pressing the clay into the plunger space, a hollow plunger 120 working through the plunger space, and means for momentarily admitting a fluid under pressure into the plunger at each stroke thereof, substantially as and for the purpose specified.

24. In a brick molding machine, a clay reservoir having a plunger space and a discharge spout; a hollow plunger working in said plunger space, a valve for momentarily admitting a fluid under pressure into the 125 130

plunger, means for actuating the valve at each reciprocation of the plunger, and a rotating worm for pressing the clay in the reservoir into said plunger space, substantially as described.

25. In a brick molding machine, a clay reservoir having a plunger space and a discharge spout; a hollow plunger working in the plunger space, a valve for admitting a fluid under pressure into the plunger, means for momentarily opening the valve at each reciprocation of the plunger, and a rotating worm for pressing the clay into said plunger space, substantially as described.

15 26. In a brick molding machine, a clay reservoir having a plunger space and a discharge spout; a hollow plunger working in alinement with said spout, a fluid pressure-operated valve for momentarily admitting a fluid under pressure into the plunger, a primary valve controlling the movements of the first named valve, means to actuate the primary valve at each reciprocation of the plunger, and a rotating worm to force the 25 material into said plunger space, substantially as described.

27. In a brick molding machine, a clay reservoir provided with a plunger space and a discharge spout; a hollow plunger reciprocating through the plunger space, means for momentarily admitting a fluid under pressure into the plunger at the end of the operative stroke of the plunger, and a rotating worm for pressing clay into the plunger space 35 when the plunger ascends, substantially as described.

28. In a brick molding machine, a clay reservoir having a plunger space and a discharge spout; a hollow plunger, having a perforated or partially open lower end, working in said plunger space, means for momentarily admitting a fluid under pressure into the plunger at each reciprocation thereof, and a rotating worm for pressing clay into the 45 plunger space, substantially as described.

29. In a brick molding machine, a clay reservoir provided with a plunger space and a discharge spout; a hollow plunger, having a perforated or partially open lower end, working in said plunger space, a valve for momentarily admitting a fluid under pressure into the plunger at each reciprocation thereof, and a rotating worm for pressing clay 50 into the plunger space, substantially as described.

30. In a brick molding machine, a clay reservoir provided with a plunger space and a discharge spout; a hollow plunger, having a perforated or partially open lower end, working 60 in said plunger space, a fluid-pressure-

operated valve for momentarily admitting a fluid under pressure into the plunger at each reciprocation thereof, and a rotating worm for pressing clay into the plunger space, substantially as described.

65

31. In a brick molding machine, a clay reservoir having a plunger space and a discharge spout; a hollow plunger, having a perforated lower end, working in said plunger space, a valve for admitting fluid under pressure into the plunger, a primary valve controlling the operation of the aforesaid valve, means for momentarily opening the primary valve at each reciprocation of the plunger, and a rotating worm for pressing clay into 70 the plunger space, substantially as described.

32. A mold conveyer comprising an elongated frame mounted upon rollers or wheels for transverse movement, two pulleys carried by said frame, a belt passing around 80 said pulleys, manually operated means for rotating one of the pulleys to move the belt longitudinally, a fixed frame, and manually operated mechanism supported by the fixed frame for causing transverse movement of 85 the movable frame and the belt, substantially as described.

33. In a fire brick molding machine, a clay reservoir in combination with a barrel communicating therewith, a plunger operable in 90 said barrel and adapted to close the opening between said reservoir and said barrel, and means for admitting fluid under pressure to said barrel when said plunger has closed said opening, substantially as described.

95

34. In a fire brick molding machine having a clay admission opening at one end and open at the other end for the discharge of clay, a plunger arranged in said barrel and adapted to move the clay admitted thereto, 100 and means for supplying fluid under pressure to said barrel when the clay therein has been set in motion by said plunger, substantially as described.

35. In a fire brick molding machine, a clay 105 throwing barrel provided with a clay admission opening at its upper end, in combination with a plunger provided in said barrel, means for admitting fluid under pressure to said barrel upon each down stroke of said 110 plunger, and a mold shifting conveyer arranged beneath said barrel, substantially as described.

In testimony whereof, I have hereunto set my hand this 11 day of July, 1906, in the 115 presence of two subscribing witnesses.

JOSEPH E. BOND.
